Primary Examiner — Karen E Kearney*Assistant Examiner* — Lilyana Bekic(74) *Attorney, Agent, or Firm* — Eva Tan(57) **CLAIM**

The ornamental design for a surgical handpiece nosecone, as shown and described.

DESCRIPTION

FIG. 1 is a perspective view of a surgical handpiece nosecone;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a top plan view thereof;

FIG. 7 is a bottom plan view thereof; and,

FIG. 8 is a cross-sectional view taken along line **8-8** of FIG. 1.

The broken lines depict portions of the article that form no part of the claimed design.

1 Claim, 7 Drawing Sheets(56)
